UNITED STATES PATENT OFFICE

CHARLES L. PHILLIPS AND INGLIS M. UPPERCU, OF NEW YORK, N. Y.

WHIRLPOOL GAME

Application filed May 2, 1929. Serial No. 359,746.

This invention relates generally to new and useful improvements in games and has more particular reference to a novel whirl-pool game.

The invention has for an object the provision of a game in which a ball is driven in a whirl-pool provided with openings of different prize values in the base of the whirl-pool to permit the ball to fall thru and requiring skill of the player to cause the ball to seek the higher prize openings, the whirl at its center to have a depressible plate arranged to ring a bell upon the resting of a ball thereon and to constitute the highest prize, the openings to be surrounded by inclined base portions arranged adjustably for changing the ease with which a ball may enter.

For further comprehension of the invention, and of the object and advantages thereof, reference will be had to the following description and accompanying drawings, and to the appended claims in which the various novel features of the invention are more particularly set forth.

In the accompanying drawing forming a material part of this disclosure:

Fig. 1 is a plan view of a device constructed according to this invention.

Fig. 2 is a plan view of Fig. 1 with the top partition removed.

Fig. 3 is a side elevational view of the device.

Fig. 4 is a fragmentary sectional view taken on the line 4—4 of Fig. 1.

Fig. 5 is a view similar to Fig. 4 but disclosing a modification.

Fig. 6 is an enlarged fragmentary sectional view taken on the line 6—6 of Fig. 2.

Fig. 7 is a fragmentary sectional view taken on the line 7—7 of Fig. 2.

Fig. 8 is a vertical sectional view as though taken on the line 8—8 of Fig. 1, but disclosing a modified form of the device.

Fig. 9 is a fragmentary view of a portion of Fig. 2, disclosing a further modified form of the device.

The reference numeral 10 indicates generally the sides of a frame having a base 11. This frame is supported in an inclined po-

sition by legs 12 having rubber feet 13. The angle of inclination provides that the lowest portion of the frame is at the front and rises to the rear.

A partition 14 is supported within the frame and above the base 11 and commences at a short distance from the front of the frame and terminates at the rear. A guideway 15 is formed upon the partition and starts with a straight portion 16 arranged along one of the sides of the frame and terminates at the rear of the frame in a whirlpool as indicated by reference numeral 17. At the lowest portion of each of the turns of the whirlpool an aperture 18 is formed in the partition 14 so that a ball moving along in the path of the whirlpool may fall thru any one of these apertures upon the bottom 11.

At the center of the whirlpool the partition is formed with a star opening closed by a star plate or other shaped plate 19. This star plate is supported upon a bracket 20 pivotally mounted on the bottom of the partition 14 and normally held in a position so that the star plate is in the same plane as the plane of the partition by a spring 21. The bracket 20 is formed with a contact arm 22 engageable with stationary contacts 23 in an electric circuit 24 including a bell 25 and batteries 26. The bell and batteries and stationary contacts are all supported upon the bottom-side of the partition 14.

Baffle plates 27 are mounted upon the bottom 11 and are arranged to direct balls falling thru the openings 18 to the front of the device and against a gate 28. Reference numeral 29 in Fig. 1 indicates a coin slot which may be formed in the partition 14, and 30 a plunger slidably arranged in the partition. A means may be provided, said means being hereinafter described, so that when a coin is placed in the coin slot and the plunger depressed, the gate 28 may move for permitting all or a certain number of the balls held between the baffle plates to empty into the front portion of the frame which is reachable by a player, such a portion being indicated by reference numeral 31. The partition 14 in the vicinity of the apertures 18 is in-

clined as indicated by reference numeral 32 in Fig. 4 so as to offer resistance to a ball passing around the whirl-pool for entering the openings due to the lowered portion of the partition. Inertia will tend to cause the ball to pass any of the specific openings.

In the modified form of the device illustrated in Fig. 5, the partition 14' has been illustrated with a flexible portion 33 surrounding each of the openings 18. A lever 34 is connected with the flexible portion and pivotally mounted as at 35 upon the main portion of the partition 14. The rear end of the lever 34 is engageable between any of the teeth to a rack 36 pivotally mounted as at 37 on the bottom of the partition 14' and urged into engagement with the lever 34 by a coaxial spring 38. The rack 36 may be coaxially moved to free the free end of the lever 34 and the inclination of the flexible portion 33 surrounding the opening 18 may be adjusted for changing the speed qualifications of a passing ball for entering the openings 18.

In operation of the device a player receives all or a certain number of the balls contained between the baffle plates 27 and normally holds these balls in the reachable portion of the frame indicated by reference numeral 31. He then takes one of the balls at a time and throws or otherwise causes the ball to pass along the guideway 16 and thru the whirl 17. Depending upon his skill or luck the ball will enter the higher prize valued openings 18. The player keeps playing until all of his balls are used and then the value of his prize is computed according to his score. If the ball passes thru the entire whirl-pool and enters its center it may rebound out from the center or it may assume a position of rest upon the star plate 19. If it does the star plate will be depressed against the action of the spring 21 and close the circuit thru the bell 25 which will ring and indicate that the player has scored the highest prize value.

The plunger 30 has a stiff flexible stem 39 pivotally connected at its bottom end to the pivot point of a pair of pivoted links 40. A spring 41 normally urges the plunger into a raised position. The outer end of one of the links 40 pivotally connects with a standard 42 and the outer end of the other lever engages within a coin chute 43 in communication with the said coin slot 29. This coin chute has an offset lower portion indicated by numeral 47. A coin 45 is shown disposed within the coin slot 29 and resting against the bottom of the upper portion of the coin chute.

A bell crank 46 is pivotally mounted intermediate of its ends and one of its ends engages into the coin chute for normally holding the coin 45 in a stationary position. A coin box 44 is attached to the bottom 11 and is in line with the coin chute. The box 44 is provided with a door 48 for permitting a re-

moval of the coins. A spring 49 is coaxially mounted on the pivot of the bell crank 46 and normally urges one end of the bell crank into a niche 50 formed in a disc 51 attached upon the gate 28. The gate 28 is rotatively mounted in the bottom 11 as at 52 and is provided with a plurality of arms 53 against which the balls 55 between the baffle plates 27 rest. The bottom 11 is provided with projecting arms 54 interengaged with the arms 53 of the gate.

In operation, when a coin is dropped into the slot 29 and then the plunger 30 depressed, the links 40 are moved into an expanded position forcing the coin laterally so as to move the bell crank 46 free from the disc 51. The coin then falls thru the offset portion 47 of the chute into the coin box. When the bell crank 46 releases the disc 51, the balls of the device indicated by reference numeral 55 cause the gate to revolve and permits a certain amount of the balls to enter the accessible portion 31 of the device. After the gate 28 has made a complete revolution it will be latched in a stationary condition by the coaxial spring 49 causing the bell crank 46 to reengage in the niche 50.

In the modified form illustrated in Fig. 8, a partition 14' has been illustrated which is formed with a whirl-pool 17' the turns of which gradually rise from the outer to the inner turns approximating the shape of a conical helical spring. When a ball is caused to roll along the guideway 15, it necessarily must rise as it runs along the inner turns of the whirl-pool. This arrangement requires greater skill on the part of the player of the device for reaching the apertures 18 having higher prize values.

In Fig. 9, a horizontal gate wheel 28^a with arms 53^a has been shown rotatively mounted upon the bottom 11. Baffle plates 27' have been illustrated for directing balls between a pair of arms 53^a of the gate wheel so as to rotate the gate wheel in one direction. One of the arms of the gate wheel is provided with a rigid extension 56 engageable by the bell crank 46 for holding the gate wheel in a locked condition. When a coin is inserted in the device and the plunger 30 depressed the bell crank 46 will be momentarily moved for releasing the gate wheel.

Balls 55 rolling from between the baffle plates cause the wheel to turn, and resilient extensions 57 project from the other arms of the gate wheel for acting against the bell crank to restrain rotation of the gate wheel unless such rotation is caused by a ball acting against the arms of the wheel. When a ball acts against the arms, the resilient extensions 57 bend and permit the wheel to rotate a partial turn until the next resilient extension acts against the bell crank. In this manner the number of balls permitted to pass the

gate wheel is controlled by the number of arms that the gate wheel is formed with.

While we have shown and described the preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new, and desire to secure by United States Letters Patent is:—

1. A whirl-pool game device, comprising a frame having a bottom member supported at an inclination from the front upwards to the rear, a flat partition in the frame and above the bottom member, a guideway terminating in a whirl-pool on the partition, and the partition being formed with openings at the lowest point of each of the turns of the whirl-pool.

2. A whirl-pool game device, comprising a frame having a bottom member supported at an inclination from the front upwards to the rear, a flat partition in the frame and above the bottom member, a guideway commencing with a straight portion and terminating in a whirl-pool on the partition, and the partition being formed with openings at the lowest point of each of the turns of the whirl-pool.

3. A whirl-pool game device, comprising a frame having a bottom member supported at an inclination from the front upwards to the rear, a flat partition in the frame and above the bottom member, a guideway terminating in a whirl-pool on the partition, and the partition being formed with openings at points along the whirl-pool.

4. A whirl-pool game device, comprising a frame having a bottom member supported at an inclination from the front upwards to the rear, a flat partition in the frame and above the bottom member, a guideway terminating in a whirl-pool on the partition, and the partition being formed with openings at the lowest point of each of the turns of the whirl-pool, said partition commencing a short distance from the front of the frame, and baffle plates upon the bottom of the frame to direct balls which fall thru the openings to the front of the frame.

5. A whirl-pool game device, comprising a frame having a bottom member supported at an inclination from the front upwards to the rear, a flat partition in the frame and above the bottom member, a guideway terminating in a whirl-pool on the partition, the partition being formed with openings at the lowest point of each of the turns of the whirl-pool, flexible inserts mounted in the partition to surround the openings, and means for causing said inserts to assume various bent conditions to require different speed qualifications of a passing ball for entering the openings.

6. A whirl-pool game device, comprising a frame having a bottom member supported at an inclination from the front upwards to the rear, a flat partition in the frame and above the bottom member, a guideway terminating in a whirl-pool on the partition, the partition being formed with openings at the lowest point of each of the turns of the whirl-pool, said partition commencing a short distance from the front of the frame, baffle plates upon the bottom of the frame to direct balls which fall thru the openings to the front of the frame, and means for holding the balls between the baffle plates, permitting a limited passing of the balls as controlled by a coin.

7. A whirl-pool game device, comprising a frame having a bottom member supported at an inclination from the front upwards to the rear, a flat partition in the frame and above the bottom member, a guideway terminating in a whirl pool on the partition, and the partition being formed with openings at the lowest point of each of the turns of the whirl-pool, the turns of the whirl-pool gradually rising from the outer to the inner ones approximating the shape of a conical helical spring.

8. A whirl-pool game device, comprising a frame having a bottom member supported at an inclination from the front upwards to the rear, a flat partition in the frame and above the bottom member, a guideway terminating in a whirl-pool on the partition, the partition being formed with openings at the lowest point of each of the turns of the whirl-pool, flexible inserts mounted in the partition to surround the openings, and means for causing said inserts to assume various bent conditions to require different sped qualifications of a passing ball for entering the openings, comprising a lever connected with each insert, and means for holding the lever in various fixed adjusted positions.

In testimony whereof we have affixed our signatures.
